UNITED STATES PATENT OFFICE.

FREDERICK MYERS, OF LIVERPOOL, ENGLAND.

TYPE-WRITING MACHINE.

SPECIFICATION forming part of Letters Patent No. 442,820, dated December 16, 1890.

Application filed July 16, 1889. Serial No. 317,689. (No model.) Patented in England April 9, 1889, No. 6,093; in Germany June 4, 1889, No. 50,616; in France October 5, 1889, No. 201,128, and in Belgium October 5, 1889, No. 87,967.

To all whom it may concern:

Be it known that I, FREDERICK MYERS, engineer, a citizen of the United States, and a resident of Liverpool, in the county of Lancaster, in the Kingdom of England, have invented certain new and useful Improvements in Type-Writing Machines, (for which I have received Letters Patent in England, No. 6,093, dated April 9, 1889; in France, No. 201,128, dated October 5, 1889; in Belgium, No. 87,967, dated October 5, 1889, and in Germany, No. 50,616, dated June 4, 1889,) of which the following is a specification.

This invention relates to that kind of type-writing machines in which the type are arranged above the paper-carriage or platen upon the peripheries of one or more vertical disks, the said disk, or each disk, (if there be more than one,) being rotated into a given position for each type thereon, the relative amounts of such rotation depending upon the relative distances to which the type-key levers or mechanism in connection therewith are or is depressed. Certain portions of the mechanism are, however, applicable to type-writing machines other than the above.

The machine herein described is in some respects similar to that set forth in my former patent specification, Serial No. 310,696; and the present invention relates more especially to the operating of the type-wheel, to the locking of the same in its exact position for printing, to the spacing of the words and characters, to the locking of the platen, to the raising of the platen to print, to the subsequent automatic release of the same, and to various details of construction.

In the drawings, Figure 1 is a plan of the machine, parts being shown broken away and other parts removed. Fig. 2 is an elevation of the right-hand end of the machine. Fig. 3 is a similar view to Fig. 2, the type-wheel-locking mechanism, type-wheel, type-wheel standard, mechanism supported thereby, platen, platen-locking mechanism, &c., being removed, and parts being also broken away. Fig. 4 is a sectional view of a detached portion of the mechanism shown in Fig. 3. Fig. 5 is an elevation of the left-hand end of the machine. Fig. 6 is a section showing a

paper-clipping device. Fig. 7 is a sectional elevation on the line *x* *x*, Fig. 1, with parts removed. Fig. 8 is a detail view (sectional elevation) showing an arrangement for locking the platen during the printing operation. Fig. 9 is a similar view showing an arrangement for spacing the characters. Figs. 10 and 10^a show a detail of the type-wheel operating and the platen-operating mechanism, which will be fully described hereinafter. Figs. 11 and 12 are respectively a front and side elevation showing a modification of part of the mechanism shown in Fig. 10. Fig. 13 is a part section on line *y* *y*, Fig. 1, showing a device employed in connection with the platen-raisng mechanism and described more fully hereinafter. Figs. 14 and 15 are respectively an end and front elevation showing a slightly-modified form of type-wheel-locking mechanism and a device for preventing rebound or vibration in the type-wheel. Figs. 16 and 17 are diagrammatic views illustrating the manner of constructing the locking-wheel shown in Figs. 14 and 15. Fig. 18 shows a modified arrangement of platen-rais- ing mechanism.

A is the main frame or bed of the machine, which may be conveniently secured by legs *A*⁶ and screws *A*⁷ to a base-plate or table *A'*. Upon one end of the main frame *A* there is mounted an overhanging standard *B'*, which serves to support the type-wheel *H* and other mechanism hereinafter described, the shaft *h* of the type-wheel being extended forward, as in Figs. 1 and 2, and supported at its forward end by a standard *B*², formed, preferably, in one with the main frame. The type-wheel *H* is firmly secured to its shaft *h*, and is capable of being oscillated about and moved longitudinally upon its axis in a manner hereinafter described. The said axis, which is approximately horizontal, is placed transversely to the platen or paper-carriage *R* below it, and the type-wheel is located with its periphery in close proximity to that of the platen, as seen in Fig. 2.

The type are arranged upon the type-wheel *H* in parallel circular groups *X* *Y* *Z*, preferably three in number. One group or circle of type—as, for instance, *X*—contains the capi-

tals and the stops or signs most frequently used therewith, a second group, as Z, embraces the small letters with their usual stops, &c., while the third group Y, which is preferably the central one, includes the numerals and those stops, signs, or characters which are seldom used. By thus arranging the type in two or more parallel rows the diameter and weight of the type-wheel may be greatly reduced. Any particular group of type may be brought into position above the axis of the platen by simply pushing back or pulling forward the shaft *h* by means of the button *h*².

The type-wheel may be readily adjusted 15 and held in any of its three longitudinal positions by a spring-catch device *K*² *K*³, such as set forth in my former patent specification above cited, and which offers no impediment to the free oscillation of the wheel.

20 Each type in a group is provided with a corresponding finger or type key *C*. All the keys are arranged in a convenient manner in the front of the machine, and each key is carried by a type-key lever *C'*, which operates 25 the type-wheel by mechanism hereinafter described, and is so arranged with reference to said mechanism that when depressed it rotates the type-wheel into a different position, that position being of course the one which 30 is necessary to bring the type corresponding to the depressed key into position for printing.

The type-key levers *C'* are arranged in a parallel series, as shown in Fig. 1, and are pivoted at their rear ends on a type-key lever shaft *D*, which is supported at one end 35 in the standard *B'* aforesaid and at the other end in a lug *B*, formed, preferably, in one with the main frame *A*. The forward ends of the levers *C'* are guided by the slots *c*⁴ in 40 a comb-plate *C*², fixed to the front of the machine, as in Figs. 1 and 3. The rear ends of the levers may be held against lateral play by collars on the shaft *D*, or the said rear ends may each be provided with a tail *c*¹⁰, 45 which works in a suitable slot *c*¹¹, Figs. 1, 4, and 7, in a guide-plate *c*¹², fixed behind the shaft. The guide-plate *c*¹² may be attached to or formed in one with a bridge-piece *c*⁷, which is supported upon the short standards 50 *B*³, cast with the main frame.

Each lever *C'* is held normally in its elevated position in contact with a fixed check-rod *c*⁹ by means of a lever-elevating spring *c'*, all the springs being preferably stamped 55 out of a single piece of sheet metal, which is secured to the under side of the bridge-piece *c*⁷ by screws, as at *c*⁸, Figs. 1 and 4. The downward movement of the levers is limited by the lower ends of the comb-slots *c*⁴, which 60 are all located at the same distance from the under sides of their respective levers, so that each of the latter has the same amount of travel.

Each lever *C'* is preferably connected with 65 its shaft in such a manner that it may be readily and quickly removed when required without disturbing the other levers or the

lever-shaft. This may be accomplished by cutting away the upper portion of each lever-eye, as at *d*¹, Figs. 1 and 4, so that it bears 70 only on the lower half of the shaft's periphery. The end of the lever is simply slipped under the shaft until its eye coincides therewith, and the lever-elevating spring *c'* then presses the eye into place and retains it there. 75

The type-wheel shaft *h* carries a pinion *K*, which gears with the toothed quadrant *F*², mounted loosely upon a fixed horizontal shaft *F*, Figs. 2 and 7, projecting from the type-wheel standard *B'*. 80

F' is a second pinion, also mounted on the shaft *F* and movable with the quadrant *F*². The pinion *F'* gears with a vertical rack *F*³, secured to the side of a frame *C*⁴, which is hinged at its rear edge, as at *a*⁶, to the main 85 frame *A* of the machine, and is held normally in its raised position by a spring *c*⁵, Figs. 1, 3, and 7, inserted between a lug *c*³ on the frame and an arm *A*⁸ of the main frame. The upward movement of the frame *C*⁴ is 90 limited by a stop *c*⁹ on the frame, which rests against the type-key-lever shaft *D* or a collar thereon, as in Figs. 1, 3, and 9.

The front edge of the hinged frame *C*⁴ is provided with a projecting rib *c*¹³, which lies 95 transversely below the type-key lever *C'*, and is adapted to be struck by the same when depressed. The rib *c*¹³ is preferably inclined from one end to the other, as shown in Figs. 5 and 11, so that the striking-points of the 100 rib all lie at different distances below their respective levers, and the movement of the latter being constant each lever will when depressed depress the frame *C*⁴ to a different point, and will consequently, through the 105 gearing *F*³ *F'* *F*² *K*, rotate the type-wheel into a different position—that is, into the position required to print with the corresponding type.

Instead of an inclined rib, as shown, a stepped or curved rib may be employed, the 110 type or type-keys being arranged accordingly, or a series of adjustable screws *c*⁶, such as shown in Fig. 10, may be employed in lieu of the rib.

The type-wheel may be locked in position 115 prior to the printing operation by the following arrangement: The type-wheel shaft *h* is provided with a locking-wheel having a series of teeth on its periphery corresponding in number and relative angular position with 120 the type on the type-wheel. In order to reduce the diameter of this locking-wheel and at the same time to increase the pitch of its teeth, it is preferable to place several small wheels, (say five, such as *H*⁵ *H*⁵), side by side 125 upon the type-wheel shaft *h*, and to form each with a corresponding number of teeth *H*³, Fig. 7, (say one-fifth of the total number,) the teeth in each wheel being set in advance of the teeth in the others, as seen in Fig. 7. 130 The wheels may be formed separately, as shown in Figs. 1 and 2, or in a piece, as described hereinafter. A locking arm or lever *L*⁶, Figs. 1, 2, and 7, is arranged with its up-

- per end L in proximity to each locking-wheel H⁵, and is connected with suitable mechanism in such a manner that each time a type-key lever corresponding to the said wheel is depressed the end L of the arm is moved into engagement with the corresponding tooth H³ on the locking-wheel and arrests the motion of the latter as soon as the proper type is in position for printing by reason of the contact between the edge of the locking-arm and a fixed arm L¹¹, carried by the standard B². To effect the movement of an arm L⁶ it is pivoted at its lower end, as at L, to the main frame, at which point it is provided with a short approximately horizontal arm or projection L⁷. Each of the above projections L⁷ is engaged by a lever E, lying transversely below and in proximity to the type-key levers C' and pivoted (at its end remote from the type-wheel, as at e) to the main frame A or to a part carried by the frame. Each time a type-key lever is depressed it depresses the corresponding transverse lever E below it, preferably by means of the pins e' thereon, and the transverse lever in its turn depresses the short projection L⁷ of the corresponding locking-arm and causes the upper end L of the arm to move into engagement with its locking-wheel. The upper ends of the pins e' are placed at such a distance from their levers C' (having regard to their distance from the pivot e) that the locking-arm L⁶ only begins to move into position as the proper locking-tooth H³ is approaching it. The outer ends of the levers E may be guided by the pins e², Fig. 7, on their under sides, the said pins passing through holes in the fixed plate e³ on the main frame. After each depression of a transverse lever E it, together with its locking-arm L⁶, is returned to its normal position by a spring e', the said springs being attached to the plate e³ aforesaid. The return of the levers E is also assisted by a spring e⁸, hereinafter described. The locking-arms L⁶ are held in their normal position by the contact between their heels L⁸, Figs. 2 and 7, and the main frame, and the upward movement of the levers is limited by the stop e⁷, hereinafter described, and by the contact between the lever ends e⁶ and the lower edges of the projections L⁷.
- Each transverse lever is connected with the projection L⁷ of its locking-arm by a slightly-flexible connection e⁵ e⁶, Figs. 1 and 7, consisting of a fork-like end having a rigid under jaw e⁵ and a flexible upper jaw e⁶. This permits the free end of the lever to descend without straining any part after the arrest of an arm L⁶ by the fixed arm L¹¹ (that is, after the locking of the type-wheel) and during the further depression of a type-key lever to perform the printing operation, as hereinafter set forth. It is preferable for a similar reason to mount the pivot e of the transverse levers upon a short link E', Figs. 1, 5, and 7, or similar movable part in such a manner that the pivot may have a certain amount of downward movement. The link and pivot are up-
- held by an elevating-spring e⁸, and the upward movement of the link and the pivot ends of the levers is limited by a stop e⁷, which engages the upper side of the link.
- The locking-wheels H⁵ H⁵ and pinion K are all mounted as a whole upon the type-wheel shaft h in such a manner that the latter can be slid longitudinally without moving the wheels and pinion, the longitudinal movement of the latter being prevented by the forked bracket h³, Figs. 1 and 2, that rests in a peripheral groove h⁴ in the boss of the pinion. It will be evident that an arrangement of transverse lever and locking-arm similar to the above could be employed, though not so advantageously, with a single locking-wheel. The platen R lies transversely below the shaft h, with its periphery in close proximity to that of the type-wheel. The platen may be turned to space the lines by a milled wheel r¹⁰, such spacing being performed by a ratchet and spring-pawl device r' r² of any well-known construction. The platen is mounted in a platen-frame R', which is capable of sliding upon a bed S in a direction parallel to the platen axis.
- T is a reciprocatory spacing-rack, such as set forth in my patent specification above cited. It is conveniently mounted upon the platen-bed S by slot-and-pin connections t⁷ t⁸, Figs. 7 and 8, and is held normally in its position farthest to the right by a spring t⁶. The rack-teeth are preferably made of a pitch equal to the space required for a character or between two words, and they are engaged in one direction only by a pawl t², carried by the sliding platen-frame R', so that each time the rack is drawn along toward the left the platen is also drawn along in the same direction.
- The spacing of the words may be accomplished by a separate word-spacing lever G³, Figs. 1, 5, and 7, which is pivoted, as at G⁴, upon the main frame, preferably at its end remote from the type-wheel, and is provided at one end with an upright inclined or wedge-shaped finger G⁵, which engages a pin t⁶ on the spacing-rack T when the front end of the lever is depressed and draws the said rack and the platen along for the required distance. The movement of the lever G³ is controlled by the stop G⁶, and a spring G⁷ returns the lever after each operation into the position shown, in which position it is held by a stop G⁸. The spacing-rack is returned into its normal position by the spring t⁶ aforesaid.
- The spacing of the characters may be accomplished on the depression of a type-key lever as follows, reference being had to Figs. 1, 2, and 9: A spacing-frame P P', hinged to the main frame at its rear edge, preferably upon the pivot a⁶ aforesaid, and held normally raised by a spring P⁴, Figs. 1 and 2, carries at its front edge a spacing-bar P, which rests against the lower sides of the type-key levers, so that the frame is turned upon its hinge-

axis at each depression of a type-key lever. An approximately horizontal shaft V , journaled upon the main frame A or on the type-wheel standard B' , is provided with an approximately horizontal arm V^2 and with a more or less upright arm V' . The arm V^2 is connected by a link V^3 with the side P' of the spacing-frame, whereby the arm is drawn downward at each depression of said frame by a type-key lever, so that the upright arm V' , which engages a pin t' or its equivalent on the spacing-rack T , is moved sidewise and slides the said rack (and consequently the platen) a distance sufficient to space a character. The connection between the link V^3 and arm V^2 is made by an elongated slot v^6 in the upper end of the link, through which the end of the arm projects, and a stiff spring v^7 is inserted between the upper side of the arm and the upper end of the slot v^6 , for a reason which will appear hereinafter.

The platen R may be locked prior to each printing operation as follows: A rack T' , Figs. 2 and 8, having its teeth of the same pitch as the aforesaid spacing-rack T , is secured to the sliding platen-frame R' , preferably on its under side. A pivoted pawl T^2 , carried by the bed S , which supports the platen-frame, is raised into engagement with the rack T' as soon as the platen has been moved the required distance and locks it during the subsequent printing operation. The raising of the pawl T^2 may be accomplished by any suitable means, such as by a sloping projection or shoe T^8 , which is carried by the sliding spacing-rack T , and in its movement forward with the rack engages and raises a projecting pin T^4 on the aforesaid pawl, so that the pointed extremity of the latter is placed in front of the rack-tooth above it and prevents the further movement of the rack and platen. The shoe T^8 is returned with the rack T by the spring t^5 , and the pawl is withdrawn from the rack by the contact between the upper side of the shoe and the pawl-pin T^4 .

The bed S is hinged, so that it and the platen thereon may be raised toward the type-wheel to perform the operation of printing. It is preferable to hinge the bed upon a pivot s^5 at the left end of the bed—that is, at its end remote from the type-wheel—as by this means there is no danger of producing a smeared impression when the paper is pressed against the type. The free end of the bed S is provided with a tubular projection s^{10} , Figs. 2 and 8, which rests upon a projection s^7 on the machine-bed A , and thus supports the bed S normally in the same position. The projection s^7 is also provided with an upright pin s^8 , which rests within the tubular projection s^{10} and serves to prevent any lateral movement in the bed S while it is rising and falling during the working of the machine. The weight of the bed, platen, &c., is also taken off the platen-raising mechanism, hereinafter described, by means of a spring s^9 , surrounding the projection s^7 .

The printing operation is performed by raising the right-hand end of the bed S and the platen by the action of a type-key lever 70 during the latter portion of its travel and after the adjusting and locking of the type-wheel.

To allow of the above further depression of a type-key lever without a corresponding movement in the type-wheel and its connecting mechanism, the lever-shaft D is made capable of a certain amount of upward movement. To this end it is mounted in elongated slots d^3 in the standard B' and lug B , 80 its rotary movement being prevented by the facets d^8 on its extremity. (See Fig. 5.) The shaft is locked in its lowest position by a sliding locking-bar D' , Figs. 1, 2, 3, 4, 5, and 13, which is mounted in the standard B' and lug B aforesaid directly above the shaft. The bar D' carries two projecting pieces D^2 , Figs. 3 and 13, on its under side, which bear against the upper faces of two pins or projections D^3 on the lever-shaft. The end of 90 the bar D' beyond the standard B' has a forked piece D^4 , Figs. 2 and 13, which is engaged by an approximately upright arm D^5 , carried by the arm V^2 aforesaid, so that each time the spacing-frame P^2 , connected with 95 said arm, is depressed by a type-key lever the locking-bar D' is slid toward the left, and at the proper moment the projections D^2 on the bar are clear of the pins D^3 on the shaft. The bar D' prevents the upward movement 100 of the shaft until a lever C' has depressed the frame C^4 into its proper position for adjusting the type-wheel. The latter is at this moment firmly locked, as above described, and the frame C^4 is unable to descend farther. 105 At the same moment the movement of the bar D' has released the shaft D , so that the continued pressure on the front end of the type-key lever causes it to turn about the rib c^{12} as a fulcrum and to raise the shaft D with its rear end, thus permitting such additional downward movement in the front end 110 of the type-key lever as is necessary to perform the printing operation in the manner hereinafter described. On the release of the 115 lever C' the shaft is returned to its normal position by springs d^4 , which are attached to the main frame A and press downward upon links d^5 , Figs. 3 and 13. These are hooked over the shaft at each end thereof, and each 120 carries a projecting pin d^6 or its equivalent, upon which rests the forked end of the spring d^4 . The locking-bar is returned into its normal position on the release of the lever by the spacing-frame spring P^4 . 125

Instead of the above arrangement for permitting an additional movement in the type-key levers, the following device may be employed, reference being had to Figs. 10 and 10^a: The vertical rack F^3 , which serves to 130 transmit the movements of the hinged frame C^4 to the type-wheel through the medium of the gearing F^2 F^1 K aforesaid, is mounted upon the hinged frame, as shown, in such a

manner that it is capable of sliding thereon for a limited distance in an approximately vertical direction. The rack is connected to the hinged frame C⁴ by a suitable spring f⁴, 5 which is attached to the frame at f⁵ and holds the rack down in the position shown, with its projecting lug f⁶ resting against the top of the frame. The spring is preferably connected to the rack in a movable manner, 10 such as by the headed pin f⁷, which passes through a slot f⁸ in the end of the spring, and a recess f⁹ is formed in the frame to give the spring freedom of movement. The spring f⁴ is of such a strength that the rack is prevented 15 from sliding upon the frame until such time as the type-wheel has been locked in position by one of the arms L⁶. The shaft D has in this case no vertical movement, and the continued pressure on the type-key lever 20 depresses the hinged frame C⁴ in defiance of the spring f⁴ and without moving the rack F³, as the latter is held firmly by its engagement with its pinion F'. During the above 25 additional movement of any type-key lever the latter depresses a pivoted frame J J' J² by means of a bar J at the front of the frame and lying transversely below the levers. The frame is capable of turning about its rear edge J³, and is provided at one end with a 30 rearwardly-projecting arm J³, the toe J⁴, Figs. 2 and 3, of which rests normally against a piece J⁵, mounted on the under side of the hinged platen-bed S, so that the depression of the front portion of the frame by the lever C' 35 causes the plate R to be raised against the type-wheel. The toe J⁴ of the arm J³ has a salient upper end, which rests against a salient projection j on the piece J⁵. The latter is pivoted, as at j', upon the bed S, the pivot 40 being placed to the rear of the toe, so that during the upward movement of the toe the latter tends to press the forwardly-projecting toe j² of the piece J⁵ against the under side of the bed S. The relative positions 45 of the salient end of the toe J⁴ and the salient projection j are such that as soon as the paper on the platen has been pressed against the type the slight forward movement of the toe J⁴ (due to the oscillation 50 of its arm J³) causes the projection j to slip off its salient end, and thus allows the bed and platen to fall to their original positions. The downward movement of the lever C' is immediately arrested by the lower end of its 55 guiding-slot c⁴, and the frame J J' J² is returned into its normal position against the stops J⁶, Figs. 2 and 5, by the flat spring J⁷. The pivoted piece J⁵ is returned to its original position by the counter-balance j⁸. 60 To prevent the above increased movement of the type-key levers from interfering with the proper working of transverse levers E by straining their flexible connections e⁵, it is preferable to pivot the latter levers upon the 65 movable link E', as aforescribed, so that they may move downward more or less bodily during such increased movement. The said

increased movement also causes the spacing-frame P P' to be depressed after the spacing operation, and this additional movement in 70 the spacing-frame is permitted without a corresponding movement in the spacing-rack by the stiff spring v⁷, Fig. 9, aforesaid, which is of such a strength that it will not yield until the movement of the arm V² has been arrested 75 by the locking of the platen.

Instead of actuating the platen - raising frame J J' J² during the latter portion of a key-lever's travel, as above described, the frame may be depressed by means of a separate lever immediately after the movement of a type-key lever has been arrested by striking the bottom of its guiding-slot c⁴. This arrangement may be understood by reference to Figs. 1 and 18. A lever J⁶ is mounted at 85 its rear end upon the main frame, preferably upon the check-rod c², and is connected in any suitable manner with the front bar J of the frame, as by a stem j⁴, which rests normally against the upper side of the rod. The 90 lever is provided at its forward end with a finger-key j⁵, and its position in plan may be seen in dotted lines in Fig. 1. When a separate printing-lever J⁶ is employed, the lower ends of the lever-guiding slots c⁴ or the upper edge of the rib a⁸ are or is placed at such a shorter distance from the under sides of the levers C' that the latter will be brought to a standstill at about the same point that they would otherwise have come in contact 100 with the bar J. The above arrangement obviates the necessity of providing a vertical movement for the lever-shaft D (or of making the rack F³ movable upon its frame C⁴) and of providing a spring-connection v⁶ v⁷ in 105 the spacing mechanism.

Instead of forming the locking-wheels separately, as in Figs. 1 and 2, they may be formed in a piece as follows, reference being had to Figs. 14 to 17: The rim of the combined wheel 110 is stamped out of a piece of sheet metal h⁵ in the form shown in Fig. 17, the locking-teeth H⁸ being formed by the stepped edges of the diagonal bars h⁶. This strip of metal h⁵ is then bent round a skeleton boss h⁷, as in Fig. 115 16, and securely soldered or brazed to it, the adjacent ends h⁸ being also firmly united in a similar manner. The steps in the bars h⁶ are so located that when the wheel is complete, as in Figs. 14 and 15, their relative angular positions correspond to those of the type on the type-wheel. To prevent the rim of the boss from interfering with the movement of the locking-arms L⁶, and also to still further lighten the wheel, the said rim is cut 125 away, as at h⁹, Fig. 16, after the rim h⁵ of the wheel has been attached. The arrow at the top of Fig. 17 shows the direction in which the teeth H⁸ engage the locking-arm L⁶. By the above construction a very light, cheap, 130 and sufficiently strong locking-wheel is obtained.

To prevent any rebound or vibration in the type-wheel during the operation of printing

when the machine is being worked rapidly, an arrangement, such as shown in Figs. 14 and 15, may be employed to lock the said wheel in an opposite direction after its movement 5 in one direction has been arrested by one of the arms L^6 . The forward edge of the locking-wheel rim h^5 is provided with a series of notches or teeth h^{10} , which may be stamped out at the same time as the rim itself. (See 10 Figs. 16 and 17.) The perpendicular—that is, the working—faces of these teeth face in an opposite direction to the working-faces of the teeth H^3 , and they are placed in the same relative angular position as the said teeth H^3 . 15 One of the teeth h^{10} is engaged by the salient end N of a locking-arm N' after the type-wheel has been arrested by one of the arms L^6 aforesaid. The dotted arrow at the foot of Fig. 17 shows the direction in which the 20 rebound of the type-wheel would take place. The arm N' is pivoted, as at n , to the main frame A, near which point it is provided with a lateral arm N^2 , projecting toward the rear of the machine and having a depending forked 25 extension N^3 . The upper branch of this fork rests normally on the upper edge of the side J' of the platen-raising frame $J J' J^2$, while the lower branch of the fork is located at a short distance below the lower edge of the 30 said side. During the first portion of the downward movement of the frame $J J' J^2$ the arm N' falls toward the rear of the machine and its salient upper end N comes in contact with the adjacent tooth h^{10} , and during the 35 further movement of the frame necessary to complete the printing operation the said end is moved along the working-face of its tooth by the contact between the lower branch of the fork N^3 and the under side of the arm J' . On 40 the return movement of the frame the arm N' is brought back by it to its normal position and leaves the type-wheel free to revolve to its original position.

The type may be inked by an absorptive 45 inking-roller M, Figs. 1, 2, and 7, which is mounted upon an axle carried by two pivoted depending arms m . One of these arms is provided with a horizontal arm m^2 , which is pressed upward by a spring m^3 . By this arrangement the inking-roller constantly bears 50 with a yielding pressure against the type.

The sheet of paper Q, Fig. 6, is guided below the platen R by a guide-plate r^8 , Figs. 6 and 7. This guide-plate is extended at intervals 55 in the form of tongues r^9 , which hug the side and top of the platen, so that the latter, on being turned by the hand-wheel r^{10} , moves the paper forward as desired.

The mode of action of the machine is as 60 follows: The type-wheel is first adjusted by the spring-catch device $K^2 K^3$ to the group of type with which it is desired to print. A type-key C is then depressed and causes a partial rotation of the type-wheel H by means 65 of its lever C', the frame C⁴, and gearing F³, F², and K. As soon as the required type is in position for printing the wheel H is

locked by one of the arms L^6 . During the above depression of the type-key its lever C' has also depressed the spacing-frame P P' 70 and moved the platen the necessary distance by the mechanism V³, V², V, V', t', T, and t². By the time the type-wheel is locked and the platen in position the latter is locked by the pawl T² and rack T', and the locking-bar D' 75 (where such is used) has been moved so as to release the lever-shaft D. The continued pressure on the type-key now raises the shaft D (or still further depresses the frame C⁴) and actuates the platen-raising frame J J' J². 80 This frame during the first portion of its movement locks the type-wheel against rebound by the arm N', and continuing its movement it presses the paper against the type by means of its rearward arm J³ and the 85 hinged bed S. As soon as the impression is made the contact between the toe J⁴ on said arm J³ and the pivoted piece J⁵ is broken and the bed S falls, drawing the paper away from the type. Immediately afterward the movement of the type-key lever is arrested by the bottom of its slot c⁴. On releasing the said lever the whole of the parts, with the exception of the platen, are returned to their normal positions by their various returning 90 springs, &c. The machine is now ready for another or the same key to be depressed to produce the next impression.

In describing the foregoing parts of the machine it has been assumed that the matter was printed from left to right. The machine could, however, be arranged to print from right to left; also, the style of the printed characters may be varied by having a series of similar type-wheels, each bearing characters of a particular style, any one of which wheels may be readily changed for any other by taking out the screws b, Fig. 1, removing the covers b', and disconnecting the wheel from its shaft.

I declare that what I claim is—

1. In a type-writer, the combination, with an oscillatory type-wheel H and a series of depressible type-key levers C', of a series of depressible levers E, lying transversely below the said levers C' and having a series of striking-points, each located at a different distance below its respective lever C' and adapted to be struck thereby, a series of pivoted locking-arms L⁶, corresponding in number to the said depressible transverse levers E and each provided with a lateral projection engaged by one of said levers E, and a series of locking-teeth H², movable synchronously with the type-wheel and arranged, as described, in 115 circles of equal number with arms L⁶, the outer ends of which are each adapted to engage in one direction any tooth in its own particular circle of teeth, whereby the type-wheel is locked by the depression of a type-key lever prior to the performing of the printing operation, substantially as described.

2. In a type-writer, the combination, with an oscillatory type-wheel H and a series of

- depressible type-key levers C', of a series of depressible levers E, pivoted at one end upon the main frame of the machine and lying transversely below said levers C', a series of 5 striking-pins e' on said levers E, each adapted to be struck by its respective lever C' and each having its upper end located at a different distance below the same, a series of approximately upright locking-arms L⁶, pivoted 10 at their lower ends upon the main frame and each having a lateral projection L⁷, engaged by the free end of its corresponding lever E, and a similar series of locking-wheels H³, arranged side by side upon the type-wheel 15 shaft, as described, and provided with a series of locking-teeth H³, having the same relative angular position as the type and each adapted to be engaged in one direction by the upper end L of its corresponding locking-arm 20 L⁶, substantially as described.
3. In a type-writer, the combination, with a type-wheel H and a series of type-key levers C', of a series of pivoted depressible levers E, lying transversely below the said levers C', a series of striking-points e', arranged, 25 as described, on said levers E, a series of pivoted locking-arms L⁶, each engaged, as described, by its corresponding lever E, and a skeleton locking-wheel on the type-wheel 30 shaft, having a series of step-like teeth H³ arranged in its rim, as described, and each adapted to be engaged in one direction by the upper end L of its corresponding locking-arm L⁶, substantially as set forth.
- 35 4. In a type-writer, a series of parallel type-key levers C' and a series of teeth H³, movable with the type-wheel and arranged, as described, in parallel circles, in combination with a series of parallel depressible levers E, 40 corresponding in number to the said circles of teeth and lying transversely below the levers C', a series of striking-pins e' on said levers E, each arranged, as described, with reference to its respective lever C, and a series 45 of locking devices, each actuated by one of the said levers E and each adapted to engage the teeth in one of said circles in one direction, substantially as described.
5. In a type-writer, a series of pivoted type-wheel-locking arms L⁶, a corresponding series 50 of transverse arm-operating levers E, and a series of type-key levers C', adapted to depress said levers E, as described, in combination with a fixed abutment L¹¹, adapted to arrest the movement of said locking-arms, a flexible device e⁵ e⁶ on the free end of each of said levers E and engaging with a lateral projection L⁷ on its corresponding locking-arm L⁶, and an approximately horizontal link E', pivoted at one end on a fixed horizontal axis, and having at its opposite end a pivot e, forming a fulcrum for said levers E, whereby any one of the latter may be depressed by a type-key lever after the arrest of its corresponding locking-arm L⁶, substantially as and for the purpose described.
- 55 6. In a type-writer, the pivoted type-wheel-locking arms L⁶, the transverse arm-operating levers E, and the type-key levers C', adapted to depress the latter, as described, in combination with guide-pins e² for the free ends of the levers E, a fixed perforated guide-plate e³ for said pins, lever-elevating springs e⁴ e⁸, a stop e¹, limiting the upward movement of the pivot ends of said levers E, a rigid jaw 70 e⁶ on the free end of each lever E and adapted to engage the under side of a lateral projection on its corresponding locking-arm L⁶, and a heel l⁸ on each of said arms, adapted to bear normally against a fixed abutment, 75 whereby the said levers E are guided in their movements and both they and their locking-arms are returned to their normal positions after each operation, substantially as set forth.
7. In a type-writer, the combination, with a sliding platen R and a reciprocatory spacing-rack T connected therewith, as described, of a pin t⁶, projecting laterally from said rack, and a pivoted word-spacing lever G³, having 80 an upturned rear end G⁵ located normally with its inclined face in close proximity to one side of said pin, whereby the platen is drawn along to space a word at each depression of the front end of said lever, substantially as described.
8. In a type-writer, the combination, with the reciprocatory spacing-rack T, the pin t⁶ thereon, and the rack-returning spring t⁵, of a rocking word-spacing lever G³, having an inclined rear end G⁵, located as described, lever-stops G⁶ G⁸, and lever-returning spring G⁷, substantially as described.
9. In a type-writer, the combination, with a series of depressible type-key levers C' and a reciprocatory spacing-rack T, connected, as described, with a sliding platen R, of a normally-elevated spacing-frame, as P P', hinged at one edge and having its opposite edge lying transversely below and adapted to be depressed to the same point by any one of said levers, an upright oscillatory arm V', having its outer end in engagement with said spacing-rack and movable synchronously with the said frame, and suitably-proportioned mechanism connecting said arm and frame, whereby the platen is drawn along the necessary distance to space a character at each depression of a type-key lever, substantially as described.
10. In a type-writer, the combination, with a series of depressible type-key levers having a constant travel and a reciprocatory spacing-rack T, connected, as described, with a sliding platen R, of a spring-raised spacing-frame P P', hinged at its rear edge, as at a⁶, and having its front bar P lying transversely to the said levers and in contact with their under sides, an upright link V³, connected at one end to the side P' of said frame, an approximately horizontal and oscillatory arm V², engaged at its outer end by the opposite end of said link, an upright arm V', movable with said arm V², and a laterally-projecting

pin t' on the rack engaged in one direction by the outer end of the arm V' , substantially as described.

11. In a type-writer, a platen R , sliding platen-frame R' , pawl t^2 thereon, and reciprocating spacing-rack T , having its teeth adapted to be engaged in a given direction by said pawl, in combination with a similarly-pitched rack T' , movable with said frame and having its teeth adapted to be engaged in the same direction as those of the rack T , and a locking-pawl T^2 , mounted in proximity to said rack T' and not movable therewith and in engagement during each operative stroke of the printing mechanism, whereby the platen is firmly locked in position just prior to and during the moment of printing, substantially as described.

12. In a type-writer, a platen R , sliding platen R' , pawl t^2 thereon, reciprocating spacing-rack T , adapted to be engaged, as described, by said pawl, and platen-frame bed S , supporting said rack, in combination with a similarly-pitched locking-rack T' , secured to the under side of the platen-frame, a locking-pawl T^2 , mounted on the said bed S and adapted to engage said rack T' in the same direction as the engagement of the pawl t^2 and rack T , a lateral projection T^4 on said pawl T^2 , and an inclined shoe T^3 , movable with said spacing-rack T and adapted to engage said projection, as described, whereby the platen is firmly locked in position prior and during the moment of printing, substantially as described.

13. In a type-writer, the combination, with a platen-bed S , hinged at one end, as described, of a projection s^{10} on the opposite end of said bed, a similar projection s^7 on the machine-bed, serving as an abutment for the projection s^{10} , a guide-pin s^8 on one of said projections and resting within a tubular recess in the other projection, and the bed-supporting spring s^9 , surrounding both pin and projections, substantially as described.

14. In a type-writer, the type-wheel H , mechanism for locking the same, hinged frame C^4 , geared with the type-wheel, and type-key levers C' , adapted to strike the front edge of said frame and depress the same, in combination with a lever-carrying shaft D , mounted in elongated vertical bearings d^3 , a locking device holding said shaft normally in its lowest position, and means adapted to disconnect said shaft and locking device as soon as the type-wheel is locked, whereby the levers C' may be depressed after the locking of the type-wheel, substantially as and for the purpose set forth.

15. In a type-writer, a series of depressible type-key levers C' , an oscillatory spacing-frame $P P'$, adapted to be depressed by said levers, a hinged type-wheel-operating frame C^4 , also adapted to be depressed by said levers, as described, and mechanism for simultaneously locking both frame C^4 and type-wheel, in combination with a horizontal lever-carry-

ing shaft D , capable of a limited upward movement, projections D^3 on the upper side of said shaft, a sliding locking-bar D' , lying parallel to said shaft and having projections D^2 , bearing normally against the upper faces of said shaft projections D^3 , and an upright oscillatory arm D^5 , engaging said bar and movable synchronously with said oscillatory frame $P P'$, substantially as described.

16. In a type-writer, the combination of a horizontal lever-shaft D , capable of a limited upward movement, levers C' thereon, oscillatory spacing-frame $P P'$, adapted to be depressed thereby, link V^3 , connected at one end to said frame, horizontal arm V^2 , engaged by opposite end of said link, upright arm D^5 on said arm V^2 , sliding locking-bar D' , having a forked piece D^4 engaged by said arm D^5 , and projections D^2 on said bar, having their lower faces bearing against the upper faces of corresponding projections D^3 on the upper side of said shaft D , substantially as set forth.

17. In a type-writer, the combination, with a horizontal lever-shaft D , capable of a limited amount of upward movement, and a series of levers C' , each adapted to raise said shaft, as described, of the hooked links d^5 , depending from said shaft, the flat springs d^4 on the main frame, and the link-pins d^6 , engaged on their upper sides by said springs, whereby the shaft is returned to its normal position after the release of a lever C' , substantially as described.

18. In a type-writer, the combination, with a series of depressible type-key levers C' , a type-wheel H , a platen R below the same, and a hinged platen-bed S , of a platen-operating frame $J J' J^2$, hinged at its rear edge J^2 to the main frame of the machine and having its front bar J lying transversely below said levers and adapted to be struck and directly depressed thereby, and a rearwardly-projecting arm J^3 on said operating-frame connected at its outer end with the free end of the bed S , whereby the platen is raised toward the type-wheel through the medium of a depressed type-key lever, substantially as set forth.

19. In a type-writer, a series of depressible type-key levers C' , an oscillatory type-wheel H , a sliding platen R below the same, a hinged platen-bed S , type-wheel adjusting and locking mechanism adapted to be operated by any one of said levers during a definite initial portion of its downward travel, and a platen-adjusting device, also operated during such portion of any lever's downward travel, in combination with a platen-operating frame $J J' J^2$, hinged at its rear edge to the main frame of the machine and having its front bar J lying transversely below said levers and adapted to be depressed by any one of the same during a definite terminal portion of its downward travel, and a rearwardly-projecting arm J^3 on said operating-frame and connected at its outer end with the free end of the hinged bed S , whereby the platen is raised

- to print by the depression of a type-key lever after the adjusting of the platen and the adjusting and locking of the type-wheel, substantially as set forth.
- 5 20. In a type-writer, a series of depressible type-key levers C', a type-wheel H, a platen R below the same, and a hinged platen-carrying bed S, supported normally in a given position, in combination with a hinged platen-
10 operating frame J J' J², adapted to be depressed at its front edge by said levers, a rearwardly-projecting arm J³ on said frame, having an upturned toe J⁴, with a salient upper end and a salient projection j on the bed
15 S, bearing upon the said upper end and having its forward face a suitable distance in advance of the rear face of said end, whereby the platen is raised against the type-wheel and instantly falls away therefrom prior to
20 the release of the depressed type-key lever, substantially as described.
21. In a type-writer, the depressible type-key levers C', type-wheel H, platen R below the same, and hinged platen-carrying bed S, supported normally in a given position, in combination with a hinged depressible frame J J' J² below said levers, a rearwardly-projecting arm J³ thereon, a toe J⁴ on the outer end of said arm, having a salient upper end, a salient projection j, bearing, as described, upon the said end, a counterbalanced piece J⁵, carrying said projection and pivoted on the bed S, as at j', in the rear of said toe, a device j², adapted to limit the forward movement of said projection, a frame-returning spring J⁷, and frame-stops J⁶, substantially as described.
22. In a type-writer, the type-key levers C', spacing-frame P P', adapted to be depressed thereby, reciprocatory spacing-rack T, means for arresting the forward movement of said rack on the completion of the spacing operation, and mechanism, as described, connecting said frame and rack, in combination with a stiff spring-connection, as v', located at a suitable point in said mechanism, whereby the spacing-frame may be depressed by said levers after the completion of the spacing operation, substantially as and for the purpose described.
23. In a type-writer, a skeleton locking-wheel having its rim formed of a single strip h⁵ of sheet metal and having its step-like teeth H³ formed in said strip in oblique parallel rows, substantially as described.
24. In a type-writer, a type-wheel H, adapted to be turned for a limited distance from a zero-point, a series of locking-teeth H³, movable synchronously with the type-wheel and having the same relative angular position as the type thereon, and means adapted to engage any one of said teeth in one direction as soon as the type-wheel is turned through the required angle, in combination with a similar series of teeth h¹⁰, also movable synchronously with the type-wheel, a locking device adapted to engage any one of said teeth h¹⁰ in a direction opposite to the engagement of the teeth H³, and means for operating such device after said engagement of the teeth H³ and prior to the actual printing operation, whereby the rebound or vibration in the type-wheel during such operation is prevented, substantially as set forth.
25. In a type-writer, a type-wheel H, adapted to be turned for a limited distance from a zero-point, a locking-wheel on the type-wheel shaft, having a series of teeth H³, arranged as described, on its periphery, and means, as L⁶, adapted to engage said teeth in one direction, in combination with a series of teeth h¹⁰, arranged as described, on the forward edge of said locking-wheel and having their working-edges facing in an opposite direction to those of the teeth H³, an upright arm N', pivoted as at n, and having its upper salient end N located in proximity to and adapted to engage said teeth h¹⁰, a hinged platen-raising frame J J' J², adapted to be depressed, as described, after the locking of the type-wheel, and a rearwardly-projecting arm N² on the lower end of said arm N' and provided with a forked piece N³, bearing normally with its upper branch against the upper edge of the side J' of said frame and having its lower branch located at a suitable distance below the under edge of said side J', whereby rebound or vibration in the type-wheel during the printing operation is prevented, substantially as described.

In testimony whereof I have signed my name to this specification in the presence of two subscribing witnesses.
